(57) **CLAIM**

The ornamental designs for a bowling ball rack, as shown.

DESCRIPTION

FIG. 1 is a front perspective view of a bowling ball rack showing my new design;

FIG. 2 is a left side elevational view thereof, the right side elevational view, front elevational view, and rear elevational view being mirror images thereof and with bowling balls shown in broken line form for illustrative purposes only;

FIG. 3 is a top plan view thereof;

FIG. 4 is a sectional view as seen along line 4—4 of FIG. 2 showing bowling balls in broken line form for illustrative purposes; and

FIG. 5 is a bottom plan view thereof.

FIG. 6 is a front perspective view of another embodiment of a bowling ball rack showing my new design;

FIG. 7 is a left side elevational view thereof, the right side elevational view, front elevational view, and rear elevational view being mirror images thereof, with bowling balls shown in broken line form for illustrative purposes;

FIG. 8 is a top plan view thereof;

FIG. 9 is a sectional view as seen along 9—9 of FIG. 7 showing bowling balls in broken line form for illustrative purposes; and,

FIG. 10 is a bottom plan view thereof.

Selective views include in broken lines bowling balls which the rack is designed to support, such broken lines being used to show a visible environmental structure which is not part of the invention.
